Inventor
Mr. J. Williams

United States Patent Office.

MARVIN T. WILLIAMS, OF MILWAUKEE, WISCONSIN, ASSIGNOR TO HIMSELF AND JOHN LUND.

Letters Patent No. 80,581, dated August 4, 1868.

IMPROVED SCAFFOLDING.

The Schedule referred to in these Letters Patent and making part of the same.

TO ALL WHOM IT MAY CONCERN:

Be it known that I, MARVIN T. WILLIAMS, of the city and county of Milwaukee, and State of Wisconsin, have invented a new and useful Improvement in Ladders and Scaffolding; and I do hereby declare that the following is a full, clear, and exact description thereof, which will enable those skilled in the art to make and use the same, reference being had to the accompanying drawing, forming part of this specification, in which—

Figure 1 is a perspective view of my improvement when used as a scaffold.

Figure 2, a view of the ladder when extended its whole length.

Figure 3, one of the locks which hold the parts of the ladder in position when extended.

Similar letters of reference in each of the figures indicate corresponding parts.

The object of my invention is to construct a ladder, which, for all purposes for which the common ladder is used, shall be efficient, and also, by joints, braces, and locks, so constructed that it may be transformed into a scaffold quickly, and be strong and handy.

A, the side-pieces; B, rounds; C, connecting-strips; D, locks or catches; E, springs, to keep the catches in place; F, rods, to hold the lower ends of the scaffold from spreading; G, scaffold-plank; H, hooks, to hold catches D back.

Operation.

The scaffold being in the position shown in fig. 1, remove the scaffold-plank G, unhook rods F; then press the lower ends outward; this will bring the upper ends of the ladder together, when the catches D will enter the slots and hold the ends firmly together. This makes a ladder as shown by fig. 2. To make a scaffold again, press down the spring-end of catches D and hook over the end-hooks H, which will keep the projections of the catches D out of the slots in the joint-ends of the ladder; then turn the outer ends down till the position, fig. 1, is obtained. Place the scaffold-plank on any of the rounds, according to the height required; hook rods F in the eyes in the foot of the scaffold.

What I claim as my invention, and desire to secure by Letters Patent, is—

The two short ladders A, pivoted to the bars C, having the spring-catches D arranged to engage in the recesses in the ends of bars A, all constructed and arranged for use substantially as herein shown and described.

M. T. WILLIAMS.
